UNITED STATES PATENT OFFICE.

WALTER S. SMITH, OF COLUMBUS, OHIO, ASSIGNOR TO THE SMITH SCALE COMPANY, OF COLUMBUS, OHIO, A CORPORATION OF OHIO.

DESIGN FOR A WEIGHING-SCALE HOUSING.

52,756.

Specification for Design.

Patented Dec. 10, 1918.

Application filed August 9, 1917. Serial No. 185,359. Term of patent 14 years.

To all whom it may concern:

Be it known that I, WALTER S. SMITH, a citizen of the United States, residing at Columbus, in the county of Franklin and State of Ohio, have invented a new, original, and ornamental Design for a Weighing-Scale Housing, of which the following is a specification, reference being had to the accompanying drawing, forming part thereof.

The figure is a view in perspective of a weighing scale, showing my new design.

I claim:

The ornamental design for a weighing scale housing as shown.

WALTER S. SMITH.
